UNITED STATES PATENT OFFICE.

SAMUEL H. KERFOOT, OF DES MOINES, IOWA, ASSIGNOR, BY MESNE ASSIGNMENTS, TO KATHERINE KERFOOT, OF SAME PLACE, AND ELENOR S. GUMP, OF CHICAGO, ILLINOIS.

LIFT AND FORCE PUMP.

SPECIFICATION forming part of Letters Patent No. 645,084, dated March 6, 1900.

Application filed October 14, 1898. Serial No. 693,573. (No model.)

To all whom it may concern:

Be it known that I, SAMUEL H. KERFOOT, a citizen of the United States, residing at Des Moines, in the county of Polk and State of Iowa, have invented a new and useful Lift and Force Pump, of which the following is a specification.

My object is to improve the construction and increase the efficiency of double-action force-pumps as required to elevate a continuous stream and force it a greater distance with less power and labor than heretofore.

My invention consists in the arrangement and combination of elements whereby the initial end of the discharge-pipe is located within and surrounded by the mouth of the air-chamber in order that the air-pressure may be exerted around the vertical plane of the water-column in the discharge-pipe as contradistinguished from the exertion of the air-pressure at the point laterally removed and distant from the water-column in the discharge-pipe.

My invention consists, further, in the arrangement and combination of an air-chamber and air-conducting tube and water-discharge pipe with a water-chamber and cylinders and pistons, as hereinafter set forth, pointed out in my claim, and illustrated in the accompanying drawing, in which—

The letter A designates a water-chamber. B and B² are cylinders connected with the water-chamber, and C and C² are opposing pistons fixed to a rod D, that is designed to be reciprocated in the cylinders as required to lift water into the water-chamber and also force it upward therefrom.

F is an air-chamber located at some space above the water-chamber A and fixed thereto by means of an open-ended coupling-tube H, that has external screws on its ends fitted in correspondingly-screw-threaded apertures in the said chambers, as required to rigidly connect the chambers.

J is an air-tube fixed in the top of the air-chamber F to supply air thereto.

K is a discharge-pipe that has an internal screw-thread at its lower end, and L is an

open-ended extension that has an external screw at its top fitted and fixed in the lower end of the pipe K, that also has an external screw-thread at its lower end fitted and fixed into a screw-threaded aperture in the top of the air-chamber H in such a manner that the extension L will project down through the open-ended coupling-tube H into the water-chamber A to conduct water up into the discharge-pipe K, while at the same time air in the air-chamber F will press upon water in the coupling-tube H and the water-chamber A as required to serve as a cushion and to aid in maintaining a steady pressure and steady continuous flow of water through the discharge-pipe K, while the two pistons are reciprocated in their respective cylinders.

In the practical operation of my invention a steady stream and larger volume of water can be forced through a greater length of tubing or hose of a given diameter and a greater quantity of water thrown in a solid stream a greater distance and with less applied power than any other pump of the same class.

Having thus described my invention, what I claim as new, and desire to secure by Letters Patent, is—

In a pump the combination of the water-chamber A of materially-greater transverse than vertical dimension, the cylinder B located below and communicating with one end portion of the bottom of the water-chamber A, the cylinder B² located above and communicating with one end portion of the top of the water-chamber in alignment with the cylinder B, the adjacent end portions of the cylinders being spaced apart a distance at least equal to the depth of the water-chamber, pistons C, C², mounted for conjunctive reciprocation in the cylinders, a pipe H mounted in, communicating with and rising from the opposite end portion of the top of the water-chamber and open at both ends, an air-chamber F, of materially-greater dimension transversely than vertically, mounted on the upper end of the pipe H and communicating therewith, an air-pipe J mounted on and commu-

nicipating with and rising from the end portion of the top of the air-chamber adjacent the cylinder B² and closed at its upper end, and a discharge-pipe traversing the air-chamber 5 F and pipe H and extending at its lower end into the water-chamber A, the said lower end of the discharge-pipe being entirely free and

spaced apart from the walls of the pipe H and water-chamber.

SAMUEL H. KERFOOT.
